(57) **CLAIM**

The ornamental design for an anti-slip hot ironing ruler as shown and described.

DESCRIPTION

FIG. 1 is a front, bottom, and left perspective view of an anti-slip hot ironing ruler showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, top, and right perspective view thereof.

Five broken lines extending along the edge and central solid line in FIGS. 1-2 are guide lines that form part of the claimed ruler design and of the claimed ruler scale pattern.
